UNITED STATES PATENT OFFICE.

CARL E. AKELEY, OF NEW YORK, N. Y.

TRAINING CONTROL FOR LIGHT-PROJECTORS.

1,341,004.

Specification of Letters Patent. Patented May 25, 1920.

Application filed March 19, 1919. Serial No. 283,649.

(FILED UNDER THE ACT OF MARCH 3, 1883, 22 STAT. L., 625.)

To all whom it may concern:

Be it known that I, CARL E. AKELEY, a citizen of the United States, and a resident of New York city, in the county of New York and State of New York, have invented an Improvement in Training Control for Light-Projectors, of which the following is a specification.

The invention described herein may be used by the Government, or any of its officers or employees in prosecution of work for the Government, or by any other person in the United States without payment of any royalty thereon.

15 The subject of this invention is a hand training control especially adapted for searchlights.

It is desirable that a searchlight may be capable of being screened from the enemy 20 and that the operator thereof be suitably protected. It is also necessary that the light be capable of oscillation in all directions, and that such oscillations may be slow or rapid as conditions may require.

25 In locating aircraft, it is usual to pick them up by sound and then train the searchlight upon them. This makes it necessary to be able to move the light without lost motion, so that the angle of deflection may 30 be accurately indicated.

To enable the operator to train the light upon an aircraft and to keep it trained thereon, it is necessary that the operator be in a position sufficiently removed from the 35 searchlight to prevent dazzling his eyes. He should also be in such a position as not to be compelled to look down the beam of light.

The present invention is devised to attain 40 the foregoing objects in a simple and efficient manner.

With the foregoing and other objects in view, the invention resides in the combination and arrangements of parts and in the 45 details of construction hereinafter described and claimed, it being understood that changes in the precise embodiment of the invention herein disclosed can be made within the scope of what is claimed without departing from the spirit of the invention.

In the accompanying drawings:—

Figure 1 is a view in side elevation of a searchlight equipped with the invention,

and illustrating a method of mounting the device;

Fig. 2 is an enlarged longitudinal section of the hand training control taken on the line II—II, of Fig. 1;

Fig. 3 is an end elevation of the device with the end plate removed;

Fig. 4 is an enlarged detail sectional view taken on the line IV—IV of Fig. 3;

Fig. 5 is an enlarged detail taken on the line V—V of Fig. 3;

Fig. 6 is a detail plan view of the structure shown in Fig. 5;

Fig. 7 is an enlarged section taken on the line VII—VII of Fig. 2; and

Fig. 8 is a detail diagrammatic view showing the action between the gears.

Referring to the drawings by numerals of reference:—

A usual form of searchlight is shown which is mounted on a truck, 1, to render it mobile and easily transported from place to place. A turntable, 2, is provided on the truck, 1, to permit of rotation or oscillation of the searchlight about a vertical axis, and said turntable includes the standards, 3—3, which form supports for the searchlight proper and in which the trunnions, one of which is shown at 4, Fig. 2, of the light are journaled; this mounting being for the purpose of allowing oscillations of the light about a horizontal axis.

A trunnion, 4, extends outwardly beyond its standard, 3, and is formed with a longitudinally extending recess or channel for the reception of a key, 5, (see Fig. 7) which may be held in place by screws, as shown, or otherwise. The trunnion is housed in a tubular member, 6, secured to a flange, 7, which is attached to the outer face of the standard by bolts, 8, or the like and serves to hold the tubular member in place.

The parts forming the subject of this invention may be incased or housed in any suitable manner, but, has herein shown a tubular casing, 9, has a sleeve, 10, connected to one end thereof, as by shrinking, welding, or otherwise, and extending therebeyond. The extending portion of the sleeve is split longitudinally as indicated at 11, Fig. 7, and this split portion is adapted to slip over the tubular member 6. The sleeve may be bound in place on the tubular member, 6, by

suitable means, such as the split collar, 12, which embraces the projecting end of the sleeve and which is formed at the ends defining the split, with out-turned ears, 13, apertured to receive a bolt, 14, or other binding element which bolts serve to draw the ears together and bind the collar and sleeve tightly to the tubular member, 6, through the coöperation of a lever nut, 15, which is 10 threaded on one end of the bolt, 14. A cylindrical or drum like casing, 16, is connected to the outer end of the housing, 9, and serves to inclose the operating mechanism or gearing of the device.

15 A shaft, 17, herein shown as hollow or tubular, is mounted for rocking movement in and extends longitudinally of the casing, 9, and a tubular bushing or lining, 18, is connected in the inner or light end of the 20 shaft and is split longitudinally, as at 19, Fig. 7, to provide a key-way for the reception of the key, 5, whereby the shaft and trunnion are connected for simultaneous rocking movement.

25 An extension member, 20, preferably of tubular formation, is connected to the outer end of the shaft, 17, and this member is formed with an outwardly extending annular flange, 21, situated between the ends 30 of the member and abutting against the outer end of the shaft, 17. A locking ring, 22, is secured by screws or otherwise to the casing, 16, and engages the outer face of the flange, 21, for the purpose of locking 35 the shaft, 17, against rectilinear movement with relation to the housing, 9.

A segmental gear, 23, is secured by keys, 24-24, or in any other suitable manner, to the extension member, 20, and is housed 40 within the casing, 16. The segmental gear, 23, is provided with a laterally extending hub on which is loosely mounted a segmental gear, 25, and these gears are joined by resilient elements such as the coiled springs, 45 26, the hooked ends of which engage in apertures formed in the respective gears. These springs normally keep the gears, 23, and 25, in alinement, and tend, when one gear is moved in respect to the other, to 50 draw the gears back to normal or alining position. The purpose of this structure is to provide a means of preventing lost motion or backlash, as will hereinafter appear. A short shaft, 27, is suitably journaled in

55 the casing, 16, and on the shaft is keyed or otherwise secured a pinion, 28, which is in mesh with the gears, 23, and 25. Also keyed or otherwise secured on the shaft, 27, is a worm wheel, 29, which is formed with 60 a laterally extending hub, 30, forming a brake drum. A brake band, 31, is trained over the drum, 30, and the ends of this band are apertured to receive a bolt, 32, the threaded end of which extends through an 65 aperture formed in the casing, 16, and on

this extending end is threaded a wing nut, 33, which bears against the outer wall of the casing and is threaded on or off the bolt to respectively tighten or loosen the brake band and thereby increase or decrease the 70 friction between the band and the drum.

A bearing block, 34, is pivotally mounted on a pin, 35, between the upper ends of the spaced apart standards, 36-36, which are secured within the casing by screws or in 75 any other suitable manner. A worm shaft, 37, is journaled in the bearing block, 34, and is held against rectilinear movement with respect to the block by collars, 38-38, which encircle the shaft and are bound 80 thereon by set screws or other suitable means and which engage remote faces of the bearing block. The shaft, 37, extends, at its lower end, through a slot, 39, formed in the casing, 16, and projects at its upper 85 end through a slot, 40, likewise formed in the casing. A crank 41, is connected to the lower extending end of the shaft, 37, and is provided with a hand grip, 42, to permit rotation of the shaft, 37. A worm, 43, is 90 keyed or otherwise secured on the shaft, 37, and meshes with the worm wheel, 29, so that rotation of the shaft, 37, will transmit rotary motion to the worm wheel and shaft, 27, and pinion, 28, thereby rotating or 95 oscillating the segmental gears, 23, and 25, to transmit a rotating movement to the shaft, 17, and oscillate the light about its horizontal axis.

A collar, 44, loosely encircles the shaft, 100 37, at a position within the casing, 16, and toward the upper end of the shaft, and the collar is located within an annular groove formed in the shaft so as to prevent movement of the collar longitudinally of the 105 shaft. One end of a resilient element such as the retractile spring, 45, is secured to the collar, 44, while the other end thereof is connected by a bolt, 46, or in like manner to the casing, 16. This spring tends to draw 110 the shaft to one side and rock it about the pivot pin, 35, to draw the worm, 43, out of mesh with the worm wheel, but is normally restrained therefrom by a latch, 47, which is pivotally secured to the casing, 16, 115 adjacent the slot, 40, and which is notched as at 48, to straddle the shaft, 37, and hold the shaft against movement under the force of the spring, 45.

From the foregoing, it will be seen that 120 by releasing the latch, 47, the shaft, 37, will be free to swing under the force of the spring, 45, to disengage the worm from the worm wheel and free the shaft, 17, to movement independently of the gearing.

125 For the purpose of rocking the shaft, 17, under these circumstances, a cross handle, 49, is provided, which is formed with a split or bifurcated key or stem, 50, adapted for insertion in the outer end of the extension 130

member, 20, and which straddles a pin, 51, which extends diametrically of the extension member and the ends of which are suitably secured in the walls thereof. With the gearing out of mesh the shaft, 17, may be easily rocked through means of the handle, 49, to quickly turn or oscillate the light.

A ring or collar, 52, encircles the tubular extension, 20, and is connected thereto, to rotate therewith in any suitable manner and this ring is located within the casing, 16. Countersunk screws, 53, or other securing elements serve to connect an arcuate plate, 54, to the ring, 52. The plate, 54, has a flange, 55, formed about its outer edge and this flange is graduated as indicated at 56, Fig. 6, to provide a means for reading the number of degrees of deflection of the light. To aid in a proper reading of the scale or 20 graduations, a pointer, 57, is secured within the casing, 16, and terminates adjacent the flange, 55, and a sight opening, 58, is formed in the casing, 16, and is so situated as to permit a view of the pointer and of a portion of 25 the scale or flange adjacent thereto.

The casing, 16, is closed at its outer face by a plate, 59, which may be secured in place by screws, 60, or in any other suitable manner.

30 In practice the device is utilized in the following manner:—

In assembling the gearing, the segmental gear, 25, is rocked with respect to the gear, 23, so as to place the springs, 26, in proper 35 tension. The pinion, 28, is then slipped on the shaft, 27, to mesh with the teeth of the gears, 23, and 25, to prevent the gear, 25, being drawn into alinement with the gear, 23, under the force of the springs. This will 40 cause the teeth of the gears to closely embrace the teeth of the pinion, as seen most clearly in the diagrammatic view, Fig. 8, and prevent lost motion or backlash so that the reading on the scale will be of proper accuracy.

45 For the purpose of screening the light and operator, the searchlight may be located in a pit, 61, which may be surrounded by an arcuate or circular ditch or trench, 62, so located 50 that the outer end of the training control will extend thereabove; to form a support for the outer end of the training control, a

track, 63, may be provided at the inner edge of the trench.

The operator of the light may move longitudinally of the trench, 62, carrying the outer end of the training control with him thereby oscillating the light about its vertical axis. When it is desired to deflect the light to either side of the vertical, the hand 55 grip, 42, may be grasped and the shaft, 37, rotated through the crank, 41. This movement will give a comparatively slow rocking motion to the shaft, 17, and will oscillate the light about its horizontal axis. Should it 60 be desired to oscillate the light with more rapidity about its horizontal axis, the latch, 47, is swung upon its pivot to release the shaft, 37, to movement under the impulse of the spring, 45, when the shaft, 16, may be 65 manually rotated through the cross handle, 49.

Having described my invention, what I claim as new and desire to secure by Letters Patent, is:—

75 1. The combination with a searchlight mounted for oscillations about a vertical and a horizontal axis, of a hand training control connected to the searchlight and movable to oscillate the searchlight about its vertical 80 axis, gearing in the training control operable to oscillate the searchlight about its horizontal axis, means for releasing the gearing from operation, and means for oscillating the light when the gearing is released. 85

2. A hand training control, including a shaft formed for connection with an object to be operated thereby, gearing for rotating the shaft, said gearing including means for taking up lost motion, means for operating 90 the gearing, means for releasing the gearing from the gear operating means to free the shaft to independent movement and means for rotating the shaft when released from the gear operating means. 95

3. A hand training control, including a shaft, gearing connected to the shaft and operable to rotate the shaft, means for operating the gearing, means for releasing the gearing from the gear operating means to free the shaft to independent movement, and means for rotating the shaft when released from the gear operating means. 100

CARL E. AKELEY.
